CLAIM

The ornamental design for a conduit tool, as shown and described.

DESCRIPTION

FIG. 1 shows a perspective view of a conduit tool.

FIG. 2 shows a front view of the conduit tool.

FIG. 3 shows a right side view of the conduit tool.

FIG. 4 shows a left side view of the conduit tool.

FIG. 5 shows a rear view of the conduit tool.

FIG. 6 shows a top plan view of the conduit tool; and,

FIG. 7 shows a bottom plan view of the conduit tool.

The shade lines in the Figures show contour and not surface ornamentation.
